UNITED STATES PATENT OFFICE.

AUGUSTINE F. LITTLEFIELD, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,312,637.

Specification of Letters Patent.

Patented Aug. 12, 1919.

Application filed September 25, 1916. Serial No. 122,071.

To all whom it may concern:

Be it known that I, AUGUSTINE F. LITTLEFIELD, a citizen of the United States, residing at Lynn, in the county of Essex and 5 State of Massachusetts, have invented certain new and useful Improvements in Sewing-Machines; and I do hereby declare the following to be a full, clear, and exact description of the invention, such as will enable others skilled in the art to which it 10 pertains to make and use the same.

This invention relates to means by which injury to the sewing-instrumentalities or the mechanism of a sewing-machine may be 15 avoided, when unusual resistance to the advancing movement of the needle is encountered.

In sewing machines of the type employed in sewing the inseam of a welted shoe, the 20 shoe is in part guided and supported by means of a device known as a "channel-guide", this device being arranged to enter the channel in the insole and to engage the bottom of the channel at a point close be- 25 side that at which the needle passes through the between-substance of the insole. The channel-guide constitutes the means for supporting the work against the thrust of the needle, so that if any unusual resistance to 30 this thrust is incurred the strain falls upon the channel-guide, as well as upon the needle and the needle-actuating mechanism. A frequent cause of such unusual resistance is the presence of lasting-tacks in the between- 35 substance. When such a tack is encountered by the needle it subjects the needle directly to resistance. It also usually deflects the needle from its proper course, and this deflection may be in such a direction as to 40 cause the needle to strike the channel-guide. The needle when so deflected is usually broken, and the blunt stub of the needle may then press against the channel guide with the result of straining the actuating-mech- 45 anism and of breaking the channel-guide.

The object of the present invention is to 50 avoid the occurrence of excessive strain, and the liability of breakage, resulting from such causes as those just described. To this end it is proposed to mount the channel- 55 guide yieldingly, so that while it normally retains its proper operative relation to the needle, and resists the thrust to which the

needle normally subjects the work, the channel-guide may yield, in the general direction 55 of the advancing movement of the needle, whenever the normal strain is substantially exceeded, thereby guarding both the channel-guide and the needle-actuating mechanism against dangerous strains. 60

While the invention is described herein particularly in its application to an inseam-sewing machine, in which the work-supporting member is in the form of a channel-guide, it will be apparent that it may be applicable to sewing-machines of other types, 65 in which the work-supporting member has forms other than that of a channel-guide.

In the accompanying drawings Figure 1 is a side-elevation of a sewing-machine embodying the present invention. Fig. 2 is a front-elevation, partly in section, showing in detail the channel-guide and its yielding connections with the other parts of the machine. Fig. 3 is a side-elevation, and Fig. 75 4 is a plan view, of the parts shown in Fig. 2.

The invention is illustrated as embodied in an inseam-sewing machine constructed in accordance with United States Letters Patent No. 1,108,560, granted August 25, 1914 to Andrew Eppler. Said machine comprises a curved hooked needle 6, a looper 8, a channel-guide 10, and a back-rest 12, all constructed and operating in the well known 80 manner of machines of this type. The needle is arranged to move in a path concentric with a pivot-stud 14, and the needle is oscillated, and the other parts of the machine are actuated, by mechanism including 85 a cam-shaft 16 and cams 18 mounted thereon.

The channel-guide 10 has the usual lower extremity 20, which enters the channel of the insole, and, as shown in Fig. 4, the 95 needle 6 advances through the between-substance in a path of movement close to the end of the channel-guide. The present invention resides particularly in the manner in which the channel-guide is supported. As 100 shown in Fig. 2, the channel-guide is provided with a vertical shank 22, which is offset laterally from the extremity 20. This shank is journaled in a bearing-sleeve 24 integral with a slotted plate 26, this plate being fixed, by means of a binding-screw 28, to 105

a member 30 of the machine, by which the channel-guide is supported and actuated in the same manner as in said Patent No. 1,108,560. The movable connection between 5 the shank 22 and the sleeve 24 permits a swinging movement of the channel-guide relatively to the plate 26, whereas in the machine of said patent these parts are rigidly connected. This movement is controlled by 10 a torsion-spring 32, which is coiled around the shank 22, one end 34 of the spring being seated in a slot in the shank, while the other end 36 is seated in a recess in the sleeve 24. The shank is retained against endwise movement 15 by a nut 38 and a collar 40, the latter bearing against a shoulder on the shank.

The spring 32 tends to rotate the shank in a direction to swing the extremity 20 of the channel-guide inwardly, that is, toward the 20 work. Movement in this direction is limited, however, by a stop-pin 42 which projects from the channel-guide and coöperates with a stop-lug 44 depending from the sleeve 24.

The normal position of the parts is shown 25 in Figs. 2, 3 and 4, in which the spring 32 maintains the stop-pin and the stop-lug in engagement, the normal position of the channel-guide being thereby determined; but whenever the channel-guide is subjected to 30 an unusual pressure in the direction of the advancing movement of the needle the spring yields, permitting the lower extremity of the channel-guide to swing outwardly to whatever degree may be necessary to relieve the 35 parts from strain. As soon as the pressure is removed the spring returns the channel-guide to its normal position. The strength of the spring is such that it does not yield to the strains normally encountered and due to 40 the resistance of the work to the passage of the needle.

The invention is not limited to the embodiment hereinbefore described and illustrated in the accompanying drawings, but

may be embodied in various other forms 45 within the scope of the following claims.

What is claimed is:—

1. An inseam-sewing machine having, in combination, sewing-instrumentalities including a needle; a channel-guide; and 50 means supporting the channel-guide normally in operative relation with the needle, but yieldable during the work piercing stroke of the needle to permit displacement of the channel-guide when subjected to an unusual pressure in the direction of the advancing movement of the needle.

2. An inseam-sewing machine having, in combination, sewing-instrumentalities including a needle; a channel-guide; and 60 means supporting the channel-guide normally in operative relation with the needle but yieldable during the work piercing stroke of the needle to permit the channel-guide to be moved in the general direction 65 of the advancing movement of the needle.

3. An inseam-sewing machine having, in combination, sewing-instrumentalities including a needle; a channel-guide provided with a shank and a laterally-offset working-extremity; a bearing in which said shank is mounted to turn; a spring arranged to resist such turning movement in one direction; and positive means for limiting turning movement of the shank in the opposite direction. 75

4. A sewing-machine having, in combination, sewing-instrumentalities including a needle; a device for supporting the work against the advance of the needle through the work; and yielding means supporting said device normally in a fixed operative relation to the needle but yieldable during the work piercing stroke of the needle to permit movement of said device in the general direction 85 of the advancing movement of the needle.

AUGUSTINE F. LITTLEFIELD.
